Term of patent 14 years

(Cl. D90—20)

FIG. 1

FIG. 2

FIG. 4

FIG. 3

Figure 1 is a perspective view of a truck tire embodying my new design, it being understood that the full line portion is repeated through the circumference of the tire shown by means of broken lines.

Figure 2 is an enlarged fragmentary plan view of the full-line tread portion in Figure 1.

Figure 3 is an enlarged fragmentary side elevational view of the full-line portion shown in Figure 1.

Figure 4 is a sectional view taken substantially on the plane indicated by line 4—4 of Figure 2.

The dominant features of my design reside in the full-line portions of the drawing.

I claim:

The ornamental design for a truck tire, as shown and described.
